[57] **CLAIM**

The ornamental design for an enclosure for an uninterruptible power supply, as shown and described.

DESCRIPTION

FIG. 1 is a top, front, right side isometric view of an enclosure for an uninterruptible power supply, showing our new design;

FIG. 2 is a top, back, left side isometric view thereof;

FIG. 3 is a front elevational view thereof;

FIG. 4 is a top plan view thereof;

FIG. 5 is a right side elevational view thereof, the left side being a mirror image; and,

FIG. 6 is a rear elevational view thereof.

The bottom of the enclosure for an uninterruptible power supply is unornamented.
